SAFETY ELECTRICAL POWER UNIT

George F. Schmitt, South Ozone Park, N. Y.

Application September 17, 1935, Serial No. 40,937

6 Claims. (Cl. 175—294)

This invention relates to a new and useful improvement in an apparatus or unit for automatically controlling the flow of current through electrical circuits for preventing arcing and 5 sparking when grounding occurs.

The principal object of the invention is to provide a simple and efficient apparatus to allow the transmission of electric current therethrough from a source of supply to an electrically-driven 10 tool or other device or apparatus without diminution of the current flow but so arranged and constructed that in the event of the grounding of the tool in the line to which the tool is connected there will be no flash or arcing to cause body 15 shocks or fires or explosions in adjacent inflammable materials or gases and the circuit to the supply will be instantaneously cut off and cannot again be closed until the defective tool is replaced or the grounding found and repaired.

Briefly and generally considered the apparatus 20 includes the use of electrical devices such as transformers, circuit breakers, vacuum tubes and others which are so arranged, related and connected that the instant the tool or other device is grounded the amount of current which can 25 flow in the circuit is immediately limited sufficiently to prevent the occurrence of a flash or arc which limitation acts instantaneously to actuate the circuit breaker and thereby cut off the 30 flow of current from the source of supply.

The invention, furthermore, includes the provision of a vacuum-control amplifier tube provided with a negative bias so that normally there 35 is no appreciable current in its plate circuit but when a grounding occurs, the connections or devices employed are such that the grid bias in the tube is altered to a positive value which causes a greatly amplified current to flow in the plate circuit which is connected to a coil in a 40 circuit breaker to throw the same open and cause an immediate practical cessation of the flow of current to the tool or other device.

In the operation of the invention I preferably 45 employ a circuit breaker in association with a vacuum tube control device, whether that device is connected to an A. C. or D. C. circuit. The alterations for D. C. operations will later be mentioned but the association of parts illustrated in the drawing and to be presently described are for 50 A. C. circuits.

Further and more specific objects, features, 55 and advantages will more clearly appear from the subjoined specification when taken in connection with the accompanying drawing forming

part thereof and which illustrates a present preferred form of the invention.

In the drawing, the single figure is a diagrammatic representation of the unit when used in conjunction with an A. C. source of supply. 5

As shown in the said drawing, the source of supply from a cable or conductor 10 is connected to a reel or drum 11 and thence to a switch 12. This permits the control device to be readily moved about at will as a unit in a plant or shop 10 and to any desired location. To the other side of the switch 12 there is connected a transformer A which functions as ordinarily and which has a primary coil 13 and a secondary coil 14 with a center tap 15. As will be obvious, there may 15 be any number of secondary coils 14 desired, depending on the number of tools which are to be connected to the unit. The secondary coil 14 is connected to the terminals of a circuit breaker 16 the other side of which is connected to an outlet socket 17 in which a tool 17A, such as an electrically driven drill, is to be plugged. 18 represents a clip attached to conductor 19 which is preferably wound on a reel 20A, said clip being attached to the work piece 20C on which the tool 17A operates. Said conductor 19 is grounded by conductor 20B to the frame of the safety electrical power unit of the claimed invention. 25

The center tap 15 is connected to a resistor 21. Said resistor 21 is connected to the primary coil 22 of a transformer B, the other end being grounded to the frame of the unit and thereby connected to the conductor 20B. Obviously the conductor 20B may be omitted provided the work piece 20C is otherwise grounded to the unit. 30 This transformer B is preferably of the iron-core type. The secondary 23 of said transformer B is connected to the grid 24 of a three-electron vacuum tube amplifier A for the purpose of controlling the negative voltage on said grid. The 35 plate 25 of tube C is connected to one end of a coil 26 of the circuit breaker 16. The resistor 21 is provided to limit the amount of current that can be fed back to transformer A while at the same time allowing a sufficient flow of current to 40 energize transformer B. 45

Between the switch 12 and the transformer primary 13 of transformer A, conductors 27 and 28 lead to opposite ends of primary coil 29 of power pack transformer D. This transformer D 50 has three secondary coils 30, 31 and 32. These secondary coils may be wound on core of the transformer secondary A if desired. The coil 32 is connected to the terminals of filament 33 of the three-electrode vacuum tube amplifier C. 55

Coil 30 is connected to the terminals of the filament 34 of a rectifier vacuum tube E while coil 13 is connected to the other electrodes 35 and 36 of said rectifier tube. The power pack transformer D is provided to step up the voltage applied to the rectifier tube E and the function of said rectifier tube is for the purpose of changing the alternating current to direct current.

A center tap from secondary coil 30 of power pack transformer D is connected by conductor 37, first to a filter system 38 and thence to the positive side of a voltage divider 40, the filter system preferably comprising two condensers and a choke coil as indicated. Said filter system acts as an auxiliary to the rectifier tube E and its function is to remove "ripples" in the line voltage. A center tap from coil 31 connects by conductor 39 to and through said filter system 38 to the negative side of said voltage divider 40, 10 and thence to the secondary coil 23 of transformer B. A conductor 41 is preferably adjustably connected to said voltage divider 40 and is connected to a center tap of the coil 32. A conductor 42 also preferably connects the positive 15 side of the voltage divider 40 with the coil 26 of the circuit breaker 16. The function of the voltage divider is to maintain a continuous and full voltage across the terminals of the rectifier vacuum tube E.

30 In the operation of the apparatus the tool 14^A is plugged into the outlet 17 and the clip 18 is attached to the work piece 20^C. With the switch 12 closed, power is supplied to the tool through transformer coils 13 and 14 and through the circuit breaker 16, the coil 26 of which is in series with the plate circuit 25 of the vacuum amplifier tube C. The grid 24 of this amplifier tube has a normal negative bias which prevents any appreciable current flowing in the plate circuit 25 of 35 said tube C. However, said grid 24 of the tube C is connected in series with the secondary coil 23 of the transformer B, the primary of which is connected in series with the resistor 21 and to the center tap 15 of the coil 14 of the transformer 40 A. Therefore, whenever any grounding occurs a flow of current is set up from the said ground to the control line 19 and thence through the conductor 20^B to the frame of the unit, thence passing further to coil 22 through the resistor 21 to the center tap 15 of coil 14 on the transformer A.

50 The flow of current just described activates the secondary coil 23 which sets up sufficient current in the grid circuit 24 to overbalance the negative bias thereof and make the grid positive which causes a greatly amplified current to flow in the plate circuit 25 of the amplifier tube. This current being in series with the coil 26 in the circuit breaker 16 permits this coil to be energized sufficiently to trip the circuit breaker and open 55 the main supply circuit. All this is done so rapidly that the circuit is opened before a flash or arc has had time to form at the point of grounding. If an attempt is made to close the circuit breaker before the grounding is repaired the coil 26 will 60 immediately trip again and therefore prevent the flow of current to the tool until and unless the leak or defect is found and repaired.

70 The filament and grid circuits 33 and 24 respectively of the amplifier tube C are provided with direct current by the relative connections with the rectifier tube E, the terminals 34, 35 and 36 of which are connected as above described to the several coils of the secondary of the power pack transformer D, which is connected through 75 its primary 29 to the main line in front of the

switch 12. By employing the intervening filter system 38, the ripples and slight unevenness in the rectified current are smoothed out before they reach the amplifier tube as hereinbefore explained.

5 From the foregoing it will be apparent that the circuit breaker 16 between the supply of power and the tool circuit is tripped by a coil 26 which is in circuit with a vacuum tube amplifier C, the grid 24 of which has a normally negative bias 10 but which grid circuit is connected to the power line in such manner that any flow therein caused by a ground will change the grid bias from negative to positive and cause instantaneously an amplified current to flow in the trip coil circuit and 15 trip the circuit breaker. The grid of tube C may thus be said to act as a valve which automatically turns the current on or off leading to the circuit breaker when necessity requires.

20 The apparatus can be adapted to operate on D. C. lines on an isolated system such as a ship where local current is generated and not grounded. In other cases where ordinary commercial D. C. is supplied, a grounded neutral is provided such as in the Edison three-wire system and if such an adaptation is made it could be effected if the current is put through a motor-generator to isolate it from its original source. In this case the main line transformer would be dispensed with as well as the transformer coils 30 22 and 23 for which a relay would be substituted. The power pack transformer would also be eliminated and the rectifier tube and the filter system and probably the voltage divider 40. In such a system the relay mentioned would operate the 35 circuit breaker so that in this case the change would be effected mechanically instead of electrically as in A. C. operation.

40 From the above description it is obvious that there has been provided a trip coil in circuit with a device which is responsive to abnormal flow of current in the tool circuit to energize the trip coil and throw the circuit breaker. In the preferred form the device has an amplifier vacuum tube with the aforesaid trip coil in circuit with 45 the plate of said tube and its grid circuit normally negatively biased and connected to the main supply line in such manner that a grounded current will change the bias from negative to positive and thereby cause current from the plate 50 circuit to flow through the trip coil and actuate the circuit breaker.

55 While the invention has been described in detail and with respect to a present preferred form thereof it is not to be limited to such details and forms since many changes and modifications may be made in the invention without departing from its spirit and scope as is manifest.

The invention claimed is:

1. A safety system for an electrically driven 60 tool adapted to operate on a work piece comprising a self-contained unit carrying an outlet socket in which said tool is to be plugged, a power line including an electric cable connected to be plugged into a source of current supply and to feed current therefrom to said outlet socket, a circuit breaker in said power line to interrupt the current supply to said outlet socket, means to trip the circuit breaker in response to a ground of the tool winding on said tool without producing 65 a spark at the point of contact between said tool and said work piece, comprising a trip line connected to a point of intermediate potential in said power line and grounded to said unit and a second line grounded to said unit and adapted 70 75

- to be connected to said work piece to establish a direct metallic connection between said work piece and said point of intermediate potential, said trip line having a total impedance adapted to limit the current which can flow therethrough in response to a ground on said tool to a value such that sparking at the point of contact between the tool and the work piece is prevented, and means responsive to said current flow in the trip line to trip said circuit breaker. 5
5. A safety system for an electrically driven tool adapted to operate on a work piece comprising a self-contained unit carrying an outlet socket in which said tool is to be plugged, a power line including an electric cable connected to be plugged into a source of current supply and to feed current therefrom to said outlet socket, a circuit breaker in said power line to interrupt the current supply to said outlet socket, means to trip 10 the circuit breaker in response to a ground of the tool winding on said tool without producing a spark at the point of contact between said tool and said work piece, comprising a trip line connected to a point of intermediate potential in 15 said power line and grounded to said unit and a second line grounded to said unit and adapted to be connected to said work piece to establish a direct metallic connection between said work piece and said point of intermediate potential, said 20 trip line having a total impedance adapted to limit the current which can flow therethrough in response to a ground on said tool to a value such that sparking at the point of contact between the tool and the work piece is prevented, 25 30 35
3. A safety system for an electrically driven tool to operate on a work piece, comprising a unit carrying an outlet socket in which said tool is to be plugged, a transformer having a primary connected to a source of power and a secondary connected to said outlet socket by means of a power line, a circuit breaker in said power line, a trip line comprising an impedance connected by a conductor between an intermediate point on said secondary and said work piece whereby an accidental connection from the winding of 40 45 50 55
- 50 said tool to said work piece causes current to flow through said impedance at a voltage less than the full line voltage of said power line, and means responsive to the flow of current in said impedance for tripping said circuit breaker, said trip line having a total impedance adapted to reduce the current flow therethrough to a value such that sparking at the point of contact of the tool on said work piece is prevented.
4. A safety system for an electrically driven tool 60 to operate on a work piece, comprising a unit carrying an outlet socket in which said tool is to be plugged, a transformer having a primary connected to a source of power and a secondary connected to said outlet socket by means of a power line, a circuit breaker in said power line, a trip line comprising an impedance connected by a conductor between the mid-point of said secondary and said work piece whereby an acci- 65
- dental connection from the winding of said tool to said work piece causes current to flow through said impedance at a voltage of approximately half of the voltage on said power line, means responsive to the flow of current in said impedance for tripping said circuit breaker, said trip line having a total impedance adapted to reduce the current flow therethrough to a value such that sparking at the point of contact of the tool on said work piece is prevented. 10 15 20 25 30 35 40 45 50 55 60 65
5. A safety system for an electrically driven tool to operate on a work piece, comprising a unit carrying an outlet socket in which said tool is to be plugged, a transformer having a primary connected to a source of power and a secondary connected to said outlet socket by means of a power line, a circuit breaker in said power line, a trip line comprising an impedance grounded to said unit and connected to an intermediate point on said secondary whereby less than the full line voltage is applied thereto when a ground occurs on either side of said power line, a conductor having a clip to be connected to the work piece, a reel carrying said conductor and having means grounding said conductor to said unit to establish a direct metallic connection between said work piece and said intermediate point, whereby an accidental connection between the winding of said tool and said work piece causes current to flow through said impedance, and means responsive to the flow of current in said impedance for tripping said circuit breaker, said trip line having a total impedance adapted to reduce the current flow therethrough to a value such that sparking at the point of contact between said tool and said work piece is prevented. 30 35
6. A safety system for an electrically driven tool to operate on a work piece, comprising a unit carrying an outlet socket in which said tool is to be plugged, a transformer having a primary connected to a source of power and a secondary connected to said outlet socket by means of a power line, a circuit breaker in said power line, a trip line comprising an impedance grounded to said unit and connected to an intermediate point on said secondary whereby less than the full line voltage is applied thereto when a ground occurs on either side of said power line, a conductor having a clip to be connected to the work piece, a reel carrying said conductor and having means grounding said conductor to said unit to establish a direct metallic connection between said work piece and said intermediate point, whereby an accidental connection between the winding of said tool and said work piece causes current to flow through said impedance, and means responsive to the flow of current in said impedance for tripping said circuit breaker, said last means comprising a space discharge device having its plate circuit connected to trip said circuit breaker and having said impedance connected to control the grid bias thereof, said trip line having a total impedance adapted to reduce the current flow therethrough to a value such that sparking at the point of contact of said tool on said work piece is prevented. 40 45 50 55 60 65
